[57] CLAIM

The ornamental design for an interior of a mobile beauty salon, as shown and described.

DESCRIPTION

FIG. 1 is a top plan view of an interior of a mobile beauty salon showing our new design;

FIG. 2 is a cross-sectional elevation view thereof taken along line 2—2 of FIG. 1;

FIG. 3 is a cross-sectional elevation view thereof taken along line 3—3 of FIG. 1;

FIG. 4 is a cross-sectional elevation view thereof taken along line 4—4 of FIG. 1;

FIG. 5 is a cross sectional elevation view thereof taken along line 5—5 of FIG. 1;

FIG. 6 is a perspective view looking in the direction of arrow 6 rearwardly and to the right side of the interior of the mobile beauty salon; and

FIG. 7 is a perspective view looking in the direction of arrow 7 rearwardly and to the left side of the interior of the mobile beauty salon.
